A. F. JALOUREAU.

PROCESS OF MANUFACTURING WATERPROOF CEMENT PIPES.

No. 24,125.

Patented May 24, 1859.

UNITED STATES PATENT OFFICE.

ALFRED FAUVIN JALOUREAU, OF PARIS, FRANCE.

IMPROVEMENT IN MANUFACTURE OF WATER-PROOF CEMENT PIPES.

Specification forming part of Letters Patent No. 24,125, dated May 24, 1859.

To all whom it may concern:

Be it known that I, ALFRED FAUVIN JALOUREAU, of the city of Paris, in France, have invented a new and useful Method and Process of Manufacturing Water-Proof and Air-Tight Tubes or Pipes, of which the following is a full, clear, and exact description, reference being had to the accompanying drawings making part of this specification.

The nature of my invention consists in forming pipes or tubes intended as water or gas pipes, tubes for underground telegraph-wires, &c., of a number of layers of paper, cotton, flax, or other tissues, &c., lapped together, with bituminous or caoutchouc substance between each layer, so as to render the whole impermeable to air or water.

In order to illustrate my process of manufacturing these pipes, I will now, in proceeding to give the description of the operation, refer to an apparatus proper for carrying it into effect, and of which—

Figure 1 represents a vertical section.

The paper, tissue, or other suitable material intended to be used for forming the pipes or tubes has first to be wound around a roller *a*, made of wood or metal, and which is arranged at one end of the machine. In commencing the operation the end of the roll of paper, &c., is to be conveyed along the inclined plane *b* to the cast-iron cylinder *c*, care being taken to maintain the paper in a parallel direction; and as it is of the greatest importance, in order to obtain perfect work, that the paper should continue to wrap around evenly and regularly throughout the operation, a horizontal guide-bar *e*, suspended by means of two rods *d*, pivoted at their upper ends at *f*, is so arranged that by pushing it (the guide-bar) against the cylinder *c* the paper will be caused to be fed on the latter at right angles to its axis, so that the paper will wrap around evenly and with precision over the cylinder *c*, to which a revolving motion is to be communicated by means of a crank or any other suitable device. The cylinder *c* being plunged into a vessel *g* containing caoutchouc or bituminous mastic, the paper will adhere to the surface of the cylinder and after one revolution will be brought round to the upper side of the latter, when an iron mandrel *h* is to be placed over the cylinder *c*. This mandrel is

first to be covered with a paper wrapper *i*, Figs. 4 and 5, having been greased sufficiently so as to facilitate its withdrawal at the end of the operation. In putting on this wrapper *i* it is very convenient to make use of a cone similar to those used for drawing a lampwick over a cylindrical tube. Hooks *k* are then to be engaged with the axles of the mandrel, the whole lifted up to the required height by means of the lever *l*, operated by a chain *m* and adjusted in the bearing-boxes *n* in such manner as that the mandrel *h* should press slightly against the cylinder *c*. The end or border of the paper on the cylinder *c* has to be detached from it by means of any suitable instrument, in order to make it adhere to the mandrel *h*, and then, on a revolving motion being communicated to the cylinder *c* and mandrel *h* in opposite directions, the paper will be submerged into the bituminous liquid before it wraps around the mandrel *h*. When the whole roll of paper has thus been wound up around the mandrel *h*, it (the mandrel) is to be lifted up again from the bearing-boxes *n* and placed on a table *B*, made of stone or brick, and very smoothly finished on its upper surface, and then covered over with a layer of very fine sand. Two operators take hold of the mandrel *h* by its axles and roll it up and down the table until the tube acquires the proper cylindrical form and is covered with a sufficient layer of sand, when it is again replaced over a vessel containing bituminous mastic, in order to give it an outer coating; but as it is very desirable to have some easy and reliable means for regulating the thickness to be given to the outer coating I have mounted on the axis of the cylinder *c* a toothed wheel *p*, having some of its teeth cut out or removed, as is shown in Fig 8. This wheel is made to mesh into the pinion *o* of the mandrel *h*. At each revolution of the cylinder, when the toothless portion of the wheel *p* comes in contact with the pinion *o*, the mandrel is made to stop for a short time, so that the number of revolutions and the thickness given to the coating may be easily ascertained. After a sufficient outer coating has been given, the mandrel is again lifted up from the bearing-boxes and subjected to another rolling on a table similar to *B*, in order that the outer

surface of the tube should become covered with a layer of sand embodied into the bituminous mastic.

In order to accelerate the cooling of the tubes after the coating with bitumen, they are placed under a water shower arranged over the second table. After the last operation the iron mandrel *h* may be withdrawn from the tube, for which purpose it is only necessary to place it in a vertical position, when a slight knock will be sufficient to make the tube slide off the mandrel, the paper wrapper *i* having been put on a mandrel previously greased.

In order to prevent the tube from coming out of shape, a wooden mandrel may be introduced until the tube becomes perfectly dry. It is then only necessary to remove the inside paper wrapper *i* by means of a metallic brush or other suitable contrivance, and line the inner surface of the tube with a waterproof coating, which can be readily effected by pouring into the tube (one end of which having previously been closed) molten bituminous substance to about one-third or one-half of its height. By reversing the tube the liquid will pour out, leaving the whole inner surface covered with an impermeable coating.

The different stages in the process of forming the tubes are shown in Figs. 6, 7, and 9.

It may be here remarked that this process can be adapted not only to roll-paper, but also to sheet-paper and all fibrous substances, as also to thin metallic sheets, as copper, zinc, and generally to all materials which on being wrapped round can be made to adhere together either by means of a bituminous or a caoutchouc cement. This process can also be applied to tubes or pipes made of glass, earthenware, wood, or metal by wrapping around them, after first coating their outer surface with a bituminous mastic, a sufficient thickness of layers of paper, &c., and then proceeding with the whole operation as above described, whereby not only additional strength and resistance will be imparted to the tubes, but they will also be protected from oxidation or other decay.

The method adopted by me for connecting the tubes together is represented in Figs. 10, 11, and 12. Into the ends of two tubes to be jointed together is fitted a short pipe *r*, made of zinc or other suitable metal, and which is provided with a number of arms *s*, which are bent, as shown in Fig. 10. The whole is then

covered with a sleeve *t*, made in the same manner as the tubes from a composition of paper, &c., and bituminous cement, and finally molten bituminous substance is poured in through the hole at *u*, which fills the whole space between the tubes and the sleeve *t* and constitutes a strong, durable, and impermeable connection.

For laying down and connecting main pipes of a great diameter I have adopted another plan, as shown in Figs. 17 and 18. It consists in arranging two sets of tubes the one in the other in such manner that each of the joinings of the inner tubes *x* shall be covered over by the sides of an outer one *y*. The tubes are made to fit sufficiently close each other, to leave but a small space between them. When the whole has been properly adjusted, molten bitumen is poured in through the holes *u* in the outer tubes *y*, which, as it fills the whole space *z* between the two sets of tubes, will on being solidified constitute an impermeable and durable cement. The tapping may be effected in the following manner, Figs. 13, 14, and 15: After boring a hole of suitable size in the main tube for the reception of a short pipe *x'*, Fig. 14, made of india-rubber and formed with flanges at both ends, which, when inserted into the hole of the tube, will press against the inner and outer side of the tube, a suitable collar is then placed over the tube and a faucet screwed tightly into it and into the india-rubber pipe *x'*.

In forming knee-jointed connections, Fig. 16, the ends of the two tubes 2 and 3 are fitted into the enlarged ends of a knee-jointed cast pipe 1, and the space 4 between the enlargement and the tube ends filled with a bituminous cement. The edges of the tubes may be also embedded into concentric grooves formed for that purpose in the body of the casting.

Having thus described my invention, what I claim as new, and desire to secure by Letters Patent, is—

The manufacture of air and water tight tubes or pipes by the process set forth.

In testimony whereof I have signed my name to this specification before two subscribing witnesses.

ALFRED JALOUREAU.
